UNITED STATES PATENT OFFICE.

JAMES P. CUTBURTH, OF PITTSBURG, KANSAS.

CAR-REPLACER.

1,246,062.

Specification of Letters Patent. Patented Nov. 13, 1917.

Application filed August 8, 1916. Serial No. 113,766.

To all whom it may concern:

Be it known that I, JAMES P. CUTBURTH, a citizen of the United States, residing at Pittsburg, in the county of Crawford and 5 State of Kansas, have invented certain new and useful Improvements in Car-Replacers, of which the following is a specification:

This invention contemplates an improved car replacer and has as its primary object to 10 provide a device of this character employing complementary frogs for efficiently directing the wheels of a car back onto the rails and wherein the said frogs will be reversible with respect to the rails for receiving the 15 car wheels.

The invention has as a further object to provide a construction wherein the said frogs will act to effectually prevent the car wheels from riding clear over the rails to 20 become again displaced or from slipping back to derailed position after having climbed the frogs.

And a still further object of the invention is to provide a device of this character 25 wherein the frogs may be easily transported from place to place and arranged in position upon the rails.

Other and incidental objects will appear as the description proceeds and in the drawings wherein I have illustrated the preferred embodiment of the invention and wherein similar reference characters designate corresponding parts throughout the several views:

Figure 1 is a plan view showing the frogs 30 of the present invention as applied to the rails of a conventional type of railway track. Fig. 2 is an end elevation with the rails shown in section and more particularly illustrating the flanges and ribs carried by the 40 frogs.

Fig. 3 is a perspective view of one of the frogs.

Fig. 4 is a similar view of the other frog, and

Fig. 5 is a sectional view more particularly showing the detailed construction of the frogs.

In carrying out the invention, complementary frogs A and B are employed. The 50 frog A includes a body 10 preferably hollowed out to reduce the weight of the said frog. Upon its upper face, the body 10 is formed with a floor 11 sloping from a point substantially midway the ends of the frog 55 toward opposite extremities thereof and also sloping, as particularly seen in Fig. 5 of the

drawings, toward the inner side edge of the said frog. Upon its outer side, the body 10 is formed with an upstanding rib 12 provided, upon its inner face, with shoulders 13 sloping toward opposite ends of the frog. Upon its inner side, the body 10 is formed with a hook 14 adapted to engage over a rail and for convenience, the rails C and D of a conventional type of railway track have been 60 illustrated in the drawings. It will now be observed that the hook 14 is formed to engage over the rail C with the body of the frog disposed upon the outer side of the rail and resting upon the ties of the track. 65 Preferably, the frog body, as well as the hook 14 thereof is provided with a plurality of downwardly extending spurs or lugs as best seen in Fig. 3 of the drawings, for firmly holding the frog fixed with respect 70 to the rail. Formed on the body 10 of the frog, at the extremities thereof, are upstanding wheel engaging flanges or shoulders 15. These shoulders slope upwardly and inwardly upon the floor 11 as best seen in Fig. 1 75 of the drawings with the outer extremities of the said shoulders terminating immediately at the inner extremity of the hook 14 of the frog. At their inner extremities, the shoulders 15 merge into the floor 11 and as will 80 now be observed, the said floor between the inner ends of the shoulders 15 slopes continuously from the rib 12 toward the inner side of the frog, over the hook 14. Connected to the outer side of the body 10, is a 85 handle 16 which may be used in carrying the frog from place to place.

The frog B includes a body 17 which, as in the instance of the frog A, is hollowed out to lighten the frog. The body 17 is formed 90 with a floor 18 sloping from a point substantially midway the ends of the body toward opposite extremities thereof with the intermediate portion of the said floor also sloping toward the inner side of the frog. 95 The frog B is arranged inwardly of the rail D and upon the inner side thereof is formed with an upstanding rib 19 provided upon its inner face, with wheel engaging shoulders 20 sloping toward opposite extremities of the 100 frog. In this connection, it will be observed that the inclination of the shoulders 20 of the frog B conforms to the inclination of the shoulders 13 of the frog A, corresponding shoulders being adapted to co-act with 105 each other as will be presently pointed out. Upon its inner side, the body 17 of the frog 110

B is formed with a hook 21 adapted to engage over the rail D with the body of the frog seating upon the ties of the track. The frog body, as in the instance of the frog A 5 is, as more particularly seen in Fig. 4 of the drawings, provided with a plurality of downwardly extending lugs or spurs disposed for engagement with the track ties for holding the frog fixed with respect to the 10 rail. Extending upwardly from the hook 21 of the frog is a wheel engaging stop shoulder or flange 22. This shoulder slopes, as more particularly seen in Fig. 5 of the drawings, from its upper extremity inwardly toward 15 the floor 18 of the frog and is also curved or sloped longitudinally to present a convex inner face. Connected to one side of the frog is a handle 23. At a point opposite the junction of the shoulders 20 of the rib 19 of 20 the frog, the inner face of the flange 22 extends over the bight portion of the hook 21 while, at the extremities of the shoulder, the inner face thereof slopes outwardly away from and terminates upon the outer side of 25 the bight portion of the hook to provide ample clearance for the wheels of a car moving to engage with the rail D.

A pair of my improved frogs, as thus described, is arranged upon the rails of the 30 track as shown in Fig. 1 of the drawings and since the floors of the said frogs slope toward opposite extremities thereof, the frogs may be reversed with respect to the rails for receiving the wheels of a car advanced toward the frogs in either direction. Assuming a pair of wheels of a car to be 35 derailed as illustrated in dotted lines in Fig. 1 of the drawings, the said wheels upon being advanced upwardly over the floors of 40 the said frogs will be gradually lifted above the plane of the rails. At the same time, the lateral sloping faces of the frog floors will tend to shift the wheels inwardly toward the rails. However, it will be observed, in 45 this connection that as the wheels are advanced toward the summits of the floors of the frogs, the corresponding inwardly sloping shoulders 13 and 20 of the frogs A and B respectively will engage the car wheels 50 for directing the car wheels laterally upon the frogs toward the rails. Since the floors of the frogs midway their ends are provided with a relatively steep lateral inclination, the car wheels will, upon being engaged by the said shoulders, be effectually 55 directed laterally toward the rails with the adjacent car wheel abutting the shoulder 22 of the frog B.

The particular function in the formation 60 of the shoulder 22 is now to become apparent. It will be noted that the pair of car wheels will not, under ordinary circumstances, be moved to abut with this shoulder until about the time the said wheels have 65 reached the summits of the frogs since, it

is at such points upon the frogs that the floors thereof are the most steep laterally. Since the shoulder 22 curves inwardly over the tread of the rail D or over the bight portion of the hook of the said frog midway 70 the ends of the shoulder or at the summit of the frog B, the shoulder 22 will contact with the innermost car wheel to limit the lateral shifting movement of the said wheels with the flange of the innermost wheel disposed immediately over the inner edge of the tread of the rail D while the flange of the outermost wheel will be disposed immediately over the inner edge of the rail C. In this position of the car wheels, it is, 80 therefore, simply necessary to move the said wheels forwardly over the frogs onto the rails. Consequently, the shoulder 22 upon its inner face is, as previously described, curved laterally and outwardly away from 85 the bight portion of the hook of the frog to provide ample clearance for the innermost wheel when moved forwardly onto the rail B while the hook 14 of the frog B slopes laterally and inwardly to act upon the wheel 90 riding over the said frog to guide the said pair of car wheels as the wheels are advanced, onto the rails and prevent the wheels from becoming again displaced to their 95 original position.

In this connection, particular attention is directed to the presence of the shoulders or flanges 15 upon the frog A. It will be noted that these shoulders are so arranged that when the innermost wheel strikes the flange 100 22 of the frog B, the outermost wheel will be arranged at the inner side of the said shoulders. Consequently, as the car wheels are advanced forwardly upon the frogs, the shoulder or flange 15 at the further end of 105 the frog from the said wheels, will be arranged to engage the flange of the outermost car wheel for positively directing the wheels back onto the rails and overcoming any possibility of the car wheels becoming 110 again displaced. The inner faces of the said shoulders slope gradually inward in the direction of the rails and are inclined substantially in accordance with the inclination of the extremities of the shoulder 22 so that the 115 flange of a car wheel engaging either of the shoulders 15 will be gradually directed by the said shoulder to guide the outermost wheel over the rail C as the innermost wheel rides around the longitudinally curved inner face 120 of the flange 22 of the frog B. Consequently, the car wheels will be effectually moved to seat upon the rails without jars or jerks while at the same time, the said wheels cannot shift clear over the rails or cannot shift 125 to their original displaced position with respect to the rails. I, therefore, provide an exceedingly efficient type of car replacer while at the same time, the frogs may be easily transported from place to place and 130

arranged in active position upon the rails of a track as occasion may demand.

Having thus described my invention, what I claim and desire to secure by Letters Patent is:

1. A car replacer including complementary frogs having rail engaging hooks and each provided with a floor sloping toward opposite extremities thereof with the floors 10 inclined at the summits of the frogs toward the inner sides of the said frogs, coacting wheel flange engaging shoulders sloping inwardly over the said frogs at the outer sides thereof, a longitudinally curved wheel stop shoulder carried by one of said frogs with the intermediate portion of said shoulder extending over the bight portion of the hook of the frog, and wheel flange engaging shoulders carried by the extremities of the other of 20 said frogs and sloping laterally toward the ends thereof in the direction of the curvature of the extremities of said stop shoulder.

2. A car replacer including complementary frogs having rail engaging hooks and 25 each provided with a floor sloping toward opposite extremities thereof with the said floors inclined toward the inner sides of the said frogs and with the lateral inclination of the floor of one of said frogs extending 30 over the hook thereof, a wheel stop shoulder curving inwardly over the hook of the other of said frogs, and coacting wheel flange engaging shoulders sloping inwardly over the floors of the said frogs toward the summits 35 thereof.

3. A car replacer including complementary frogs having rail engaging hooks and each provided with a floor sloping toward opposite extremities thereof with the said 40 floors inclined toward the inner sides of the said frogs, wheel flange engaging shoulders arranged at the extremities of one of said frogs to slope longitudinally away from the hook of the said frog with the 45 outer ends of the said shoulders terminating at the inner extremity of the bight portion of the said hook, and a wheel stop shoulder carried by the inner side of the

other of said frogs with the said shoulder curving longitudinally from its extremities 50 at points upon the outer side of the bight portion of the hook of the frog inwardly over the said bight portion.

4. A car replacer including complementary frogs having rail engaging hooks and 55 each provided with a floor sloping toward opposite extremities thereof, upstanding coacting wheel engaging shoulders carried by the outer sides of the frogs with the shoulders of each frog sloping inwardly 60 over the floor thereof toward the summit of the frog, wheel flange engaging shoulders carried by one of said frogs at the extremities thereof and sloping longitudinally and laterally toward the outer side of the frog 65 with the floor of the frog inclined inwardly over the hook of the frog between the inner extremities of said flange-engaging shoulders, and a wheel stop shoulder carried by the inner side of the other of said frogs and 70 curved longitudinally over the bight portion of the hook of the said frog with the extremities of the said shoulder substantially conforming to the inclination of the said flange engaging shoulders of the said first 75 mentioned frog.

5. A car replacer including a frog provided with a rail engaging hook and having a floor sloping toward opposite extremities of the frog, a wheel engaging shoulder at the 80 outer side of the frog sloping inwardly over the floor of the frog, and wheel engaging shoulders upstanding from the floor of the frog at the extremities of said hook and arranged with their outer ends terminating 85 at the ends of the frog and at the inner side of the bight of the hook with the said shoulders sloping outwardly upon the frog floor toward said first mentioned shoulders and away from the hook, the floor of the 90 frog sloping smoothly at its summit laterally toward the inner side of the frog between the inner extremities of the said shoulders over the said hook.

In testimony whereof I affix my signature. 95
JAMES P. CUTBURTH. [L. S.]
